(57) **CLAIM**

The ornamental design for a case for vehicle navigation device, as shown and described.

DESCRIPTION

FIG. 1 is a front perspective view of a case for vehicle navigation device, showing my new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a bottom view thereof;

FIG. 8 is a top view thereof;

FIG. 9 is an enlarged detail view of area 9 in FIG. 3 thereof; and,

FIG. 10 is an enlarged detail view of area 10 in FIG. 3. The broken lines in the drawings illustrate the portions of the case for vehicle navigation device, which form no part of the claimed design.
